UNITED STATES PATENT OFFICE.

JOSEPH WURZER, OF CARROLL, IOWA.

DRAFT EQUALIZER.

Application filed October 19, 1926. Serial No. 142,673.

This invention relates to new and useful improvements in draft equalizers, and particularly to draft equalizers for use in connection with agricultural machines, such as 5 plows.

One object of the invention is to provide a device of this character by means of which side draft is practically eliminated, and the pull of the horses on the landside is equalized 10 with relation to the pull of the horses in the furrow.

Another object is to provide a device of this character which is simple in construction, durable in operation, and which is 15 formed of the minimum number of parts.

Other objects and advantages will be apparent from the following description when taken in connection with the accompanying drawing.

20 In the drawing:

Figure 1 is a plan view of the invention, certain of the parts being broken away, and made in accordance with the present invention.

25 Figure 2 is a fragmentary plan view of the device, with certain of the parts removed to disclose parts otherwise hidden.

Figure 3 is a rear elevation of the device.

Figure 4 is a detail sectional view on the 30 line 4—4 of Figure 1.

Referring particularly to the accompanying drawing, 10 represents a suitable frame which is secured to a plow at one end. Pivotally connected to the intermediate portion of the frame, and extending laterally from opposite sides thereof, are the draft beams 11 and 12. Pivotally secured to the frame 10, adjacent the rear end, and at one side thereof, as shown at 13, is a pair of 35 parallel links 14, said links extending obliquely and longitudinally of the frame, and having the short links 15 pivotally connected to their other ends. A guide 16, carried by the frame 10, receives the adjacent link 14 slidably therethrough, and maintains said link in close relation to the frame. The other ends of the short links 15 are 40 pivotally connected to the opposite sides of the angle portion of an angle lever 17. Secured to the opposite faces of the forward end of the frame 10, and projecting a short distance forwardly thereof, are the plates 18, and pivotally connected between the forwardly projecting ends of said plates is the 45 inner end of a short link 19. Pivotally connected to the frame 10, inwardly of the

plates 18, is a link 20, which extends forwardly and laterally from the frame, and has in its outer end, a longitudinal slot 21. This slotted end of the link 20 is pivotally 50 and slidably connected to the outer end of the adjacent arm of the angle lever 17, by means of the pivot member 22, disposed through said arm and the slot 21. Pivotally connected to the pivot member 22, at one end, and pivotally connected to the forward end of the link 19, at its other end, is a link 23. Pivotally carried by the beam 11, adjacent its inner end, are the forwardly extending parallel links 24, and disposed 55 through the forward ends of the links is the before-mentioned pivot member 22, the adjacent ends of the links 20 and 23 being disposed between said links 24.

Two horses are adapted to be hitched to each of the draft beams 11 and 12, and as the horses of the beam 12 pull a degree stronger than those of the beam 11, the links 25, which pivotally connect the other arm of the angle lever 17 with the beam 12, will 60 cause the lever 17 to be rocked, and its lateral arm carrying the pivot member 22 to push rearwardly on the links 24, and swing the beam 11 rearwardly, thus holding back the horses of the beam 11, with the result that the latter horses will have no greater leverage, than the other horses, thus 65 equalizing the pull on both beams. Thus the horses on the unplowed land cannot overbalance the pull of the horses in the 70 plowed land, but produce an equalized draft on both sides of the device, with the result that the plow will not be pulled to any greater extent toward one side than toward 75 the other.

Additional beams 12' are pivotally connected to the front of the frame 12, and have their outer ends connected to the corresponding ends of the links or beams 12, by means of the link 10', whereby said beams 12 and 12' will maintain their parallel relation, 80 during their pivotal movements.

While I have shown a form of the device which is adapted for use with a four horse team, I wish it understood that five horses 85 may be hitched to the device, by connecting three of the horses to the lever or beam on the furrow side, and two horses to the beam on the landside. In this event it becomes necessary to lengthen the beam on the un- 90 plowed land side.

110 The present device is capable of use in

connection with right or left hand plows, sulky plows, or as a three horse evener in connection with a cultivator.

What is claimed is:

- 5 A draft equalizer including a support, oppositely extending draft beams carried by the support, an angle member on the support, links connecting the angle portion of the angle member with one end of the support, a link connected with one end of the

angle member and to one of said beams, links pivotally carried by the support and pivotally connected with one end of the angle member, one of said links being slidably connected with said angle member, and links carried by the other beam and pivotally connected with the other end of the angle member.

In testimony whereof, I affix my signature.

JOSEPH WURZER.
